UNITED STATES PATENT OFFICE.

SAMUEL B. KNAPP, OF OSCEOLA, IOWA.

INSECT-TRAP.

SPECIFICATION forming part of Letters Patent No. 241,672, dated May 17, 1881.

Application filed March 8, 1881. (No model.)

To all whom it may concern:

Be it known that I, SAMUEL B. KNAPP, of Osceola, Clarke county, Iowa, have invented a new and Improved Insect-Destroyer, of which 5 the following is a specification.

The object of my invention is to provide a device for attracting insects, which drop into a poisoned liquid in the device, and are thus destroyed.

- 10 In the accompanying drawings, Figure 1 is a plan view of my improved insect-destroyer. Fig. 2 is a horizontal sectional view of the same on the line xx , Fig. 3. Fig. 3 is a cross-sectional elevation of the same on the line yy , Fig. 15 1; and Fig. 4 is a diagonal cross-sectional elevation of the same on the line zz , Fig. 2.

Similar letters of reference indicate corresponding parts.

The lantern A is provided with a bottom, B, 20 having a central aperture, C, of sufficient size to admit the lamp D, which has two lateral studs, E E. The bottom B is provided with two corresponding recesses, F F, opening into the aperture C to admit the studs E when the 25 lamp D is passed through the aperture. The lamp is then turned so that the studs E rest on the edge of the aperture C. The bottom of the lantern is considerably larger than the lamp, and has a vertical rim, G, around the outer 30 edge. This rim G forms a trough, H, around the lamp, with the inclined or vertical plates J resting upon the bottom B and supporting the panes K K of the lantern. This trough is provided with an outlet-tube, L, closed by a 35 screw-cap, M, and with a series of small overflow-openings, N N. At the four corners formed by the plates J J tubes O O pass through the bottom of the lantern, or these bent tubes may

be arranged in some other suitable manner in the trough H. The lower ends of these tubes 40 are closed by means of corks or plugs P, and the bait—preferably consisting of a sweetened liquid—is poured into the top of the tubes O O. The top of the lantern is provided with a hook, Q, for hanging it. The lantern gives a very 45 brilliant light and will attract insects from considerable distances.

The lantern can be suspended from the top of a room or from a tree, or can be placed upon a suitable support. The lamp can be inserted 50 from below very conveniently. As the cork or plug P can be drawn out of the bait-tubes O, the latter can be cleaned very easily. If too much water collects in the trough, it can flow off through the overflow-openings N N, and the liquid in the trough and the insects that have expired therein can be drawn off completely by unscrewing the cap M.

Having thus described my invention, I claim as new and desire to secure by Letters Patent— 60

1. In an insect-destroyer, the combination, with the lantern A, having a trough, H, formed around its base, of the bait-tubes O and the plugs or stoppers P, substantially as herein shown and described, and for the purpose set 65 forth.

2. In an insect-destroyer, the combination, with the lantern A, of the enlarged bottom B, the rim G, and the glass supporting-plates J, substantially as herein shown and described, 70 and for the purpose set forth.

S. B. KNAPP.
